UNITED STATES PATENT OFFICE.

JOHN W. THOMAS, JR., OF NASHVILLE, TENNESSEE.

SWITCH AND SIGNAL MECHANISM.

SPECIFICATION forming part of Letters Patent No. 488,853, dated December 27, 1892.

Application filed June 29, 1892. Serial No. 438,453. (No model.)

To all whom it may concern:

Be it known that I, JOHN W. THOMAS, Jr., of Nashville, in the State of Tennessee, have invented a new and useful Improvement in 5 Switch and Signal Mechanism, of which the following is a specification.

My invention relates to that kind of mechanism for interlocking the tappets of the operating levers of an interlocking switch and 10 signal apparatus in which the tappets and interlocking dogs are combined with intermediate means mounted on the tappets and adapted to operate on and be operated by the dogs.

15 It is my object to provide a simple and effective intermediate for the purpose, and to this end I mount upon such of the tappets as may be required for the purpose, a pendulous intermediary—which is pivoted to the tappet, 20 so that it may swing from side to side freely, and has its lower portion (corresponding in a general way to the “bob” of a pendulum) adapted to enter between the inner opposed ends of the two locking dogs between which 25 the tappet is located. When the tappet is adjusted vertically so as to bring the “bob” between the two locking dogs, then a movement of the one dog toward the tappet will through the intermediary of the pendulum—as 30 I shall call it for want of a better name—transmit movement to the other dog. There is absolutely no danger of the pendulum becoming cramped or sticking, and the device is most simple and can be applied without trouble to 35 the apparatus.

In the drawings—Figure 1 is a plan of so much of a four-tappet interlocking machine as needed for purposes of explanation. Fig. 2 is a section on line 2—2, Fig. 1. Fig. 3 is a 40 face view and Fig. 4 is an edge (side elevation) view of one of the locking dogs on enlarged scale. Figs. 5 and 6 are like views of one of the dogs which have no locking function but merely transmit movement to and 45 from a pendulum as the case may be. Fig. 7 is a view similar to Fig. 1 with the tappets in somewhat different position. Fig. 8 is a face view and Fig. 9 is an edge view of the device which I have termed a pendulum.

50 K is a stationary frame, in vertical ways in which the tappets B'—B⁴ inclusive are mount-

ed to slide in the usual way. Back of the tappets are the lock bars H'—H³ inclusive, which are mounted to slide horizontally in frame K, independently of one another. For some reasons I may prefer to mount the pendulums upon the rear face of the tappets, and for this reason I give an offset to the middle portion of each tappet that carries a pendulum (as seen more clearly in Fig. 2) so that there may be room between the tappet and the lock bar behind for the interposition of the pendulum. Thus to the rear face of tappet B² is pivoted the pendulum A²; and to the rear face of tappet B³ is pivoted the pendulum A³. 55 These pendulums are shown in dotted lines in Figs. 1 and 7; and one of them (A³) is in side elevation in Fig. 2. The construction of the pendulum is shown clearly in Figs. 8 and 9. Each pendulum is of less width than the tappet to which it is applied and is pivoted thereto at a point about midway between the edges of the tappet so that while it will hang centrally by gravity it may swing freely to each side of its center of gravity from edge 60 to edge of the tappet. And it is of such form and dimensions that when moving up and down with its tappet, it can readily enter, or withdraw from, between the two dogs between which it serves as the medium of communication. 65 On the lock bar H' are fastened two dogs I and C. One of these I has merely a miter nose to engage a V or miter notch J in the tappet, B'. The other C, has a miter nose E to engage the notch in tappet B², and a 70 rounded end D to bear against the pendulum A² pivoted to tappet B². There are two notches J on one edge of this tappet, and none on the other. On the lock bar H², are two dogs C² C. The latter is like the dog C on lock bar H' 75 already described; and its miter nose E is to engage one or the other of the two notches J on the adjoining edge or tappet B³, and its rounded end D is to operate in conjunction with the pendulum A³ on tappet B³. The other 80 dog C², has no miter nose, is not intended to lock, but simply has a rounded end D to operate in connection with the pendulum A³ on tappet B². On the third locking bar H³ are two dogs C², I, similar respectively to those 85 above described by like reference letters. 90

While the pendulums are placed upon the

rear face of the tappets, they might very well be pivoted upon their front. In that event, the two tappets B², B³, which carry the pendulums would require no offset, but might have 5 the plain straight face which their fellows B' B⁴ have; and the locking dogs would have the relative position of their noses E and rounded ends D shifted to correspond with this change in position of the pendulums.

10 Such is the construction and organization of the apparatus. Its mode of operation is as follows: In Fig. 1 all the tappets are in their normal position, the pendulum A² of tappet B² being in line with the dogs on either side of it, the pendulum A³ of tappet B³ being above the line of the dogs, and all of the tappets being unlocked. If, now, tappet B' be 15 reversed, lock bar H will thereby (through its dog I) be shoved to the right, and by its dog C will both lock tappet B² and push pendulum A² over against tappet C² of bar H², thus shoving in time bar H² to the right and locking tappet B³. But as the pendulum A³ of tappet B³ is out of line with the dogs, lock 20 bar H³ will be unaffected and consequently tappet B⁴ will remain unlocked.

25 In Fig. 6, the tappets B', B³, B⁴ are shown

reversed, tappet B² is normal, and all of the tappets are locked except B'.

From these examples the manner in which 30 the apparatus can be used will be understood without further explanation by those skilled in the art to which my improvement relates.

Having described my invention and the manner in which the same is or may be carried 35 into effect, what I claim and desire to secure by Letters Patent is:

In combination with the sliding locking bars and their attached dogs, the vertical longitudinally movable notched tappets provided 40 with pendulums A², A³ of less width than the tappets, pivoted to said tappets to hang vertically by gravity and capable of swinging freely to each side of their center of gravity from edge to edge of the tappets to which they 45 are severally attached, as hereinbefore set forth.

In testimony whereof I affix my signature in presence of two witnesses.

JOHN W. THOMAS, JR.
